N. C. DE LOSS

1,720,886

DOOR HOLDER

Filed June 11, 1927

Norman Claybough De Loss,
Inventor
By Frank W. Strong, Attorney.

UNITED STATES PATENT OFFICE.

NORMAN CLAYBAUGH DE LOSS, OF SHAKER HEIGHTS, OHIO.

DOOR HOLDER.

Application filed June 11, 1927. Serial No. 198,258.

My invention relates to doors and more particularly it relates to an improved door holding device adapted to retain doors, such as garage doors and the like, opened.

5 An object of my invention resides in the provision of an improved door holder capable of maintaining a door, when opened, from accidentally closing by the action of extraneous forces, and which may be readily released to 10 permit the door to be closed.

Another object of my invention resides in the provision of an improved door holder which may be manually disconnected to enable the door to be swung to open to an ex- 15 tended position relative to its closed position.

Another object of my invention resides in the provision of an improved door holder which is comprised of few parts, all formed from a minimum amount of stock rendering 20 the same economical to produce, which parts may be readily applied to numerous types of doors, and are at the same time durable, serviceable, and positive in operation.

These and other objects of my invention 25 and the invention itself will become apparent from reference to the following description of an embodiment thereof, and in which description reference will be had to the accompanying drawings, forming a part of this 30 specification.

Referring to the drawings:

Fig. 1 is a perspective view of an embodiment of my invention attached to a hinged door and looking down upon the same, and 35 illustrating the door opened;

Fig. 2 is a like view of the same illustrating the door closed;

Fig. 3 is an enlarged transverse sectional view taken on the line 3—3 of Fig. 1;

40 Fig. 4 is an enlarged top plan view taken on the line 4—4 of Fig. 2;

Figs. 5 and 6 are side elevational views illustrating the embodiment of my invention when the door is in opened or closed positions, respectively; and Fig. 7 is a side elevation of a modification of a portion of the foregoing embodiment.

Referring to all the figures of the drawings in all of which like parts are designated

by like reference characters, in which figures, 50 I have illustrated an embodiment of my invention applied to one of a pair of swinging doors 20, preferably comprising a rod 1 formed preferably of round metallic stock, and bent substantially U-shape, there being preferably a pair of laterally extending parallel arms 2 and 3 with terminating lateral securing flanges 4 and 5 disposed at right angles to the rod 1. Said flanges are flattened and are apertured for the reception 60 of securing bolts 6 to hold the rod on the inner side 7 of a door 20 adjacent the edge 12 thereof, which is hingedly connected to a door jamb 13 by hinges 14. The rod 1 is preferably disposed on a vertical plane and parallel relative 65 to the door edge 12, and is spaced from the door by virtue of the arms 2 and 3.

A link 10 having a looped outer end 11 is provided, and an eyelet 14 formed by said loop is adapted to receive the rod 1 to enable 70 the looped end of the link to slide upwardly or downwardly on the rod 1 when the door is being swung either into opened or closed position. The link is of a length substantially 75 equal to the length of the rod and when the door is in closed position, the loop 11 is disposed at the junction of the arm 3 and rod 1, as best shown in Fig. 5. While in closed position the loop is positioned as shown in Fig.

6 with the link substantially parallel to the 80 rod. The link 10 is bent at 15 to permit the loop 11 to assume a position at an angle relative to the rod 1 when the door is open or closed. As best shown in Fig. 5 of the drawings, that is when the door is closed the link is disposed on a horizontal plane substantially at right angles to the rod 1 by virtue of its pivotal connection to a bracket 18 on the door jamb 13 and the loop 11. It will be 85 apparent from the relative positioning of the rod and link that all forces tending to close the door will be communicated to the link which cannot move upwardly or downwardly on the rod by virtue of its position relative to the rod 1, when the door is open, and accordingly the door is held against accidental closing by the action of extraneous forces upon the door, such as wind. 95

The inner end of the link 10 is bent downwardly at right angles to provide a finger 17 which is adapted to cooperate with the bracket 18 formed from a round stock of metallic material, which is looped at 19 intermediate its ends to form an eyelet 21 into which the finger 17 is projected. Said finger and bracket comprise a universal pivot for the link to permit it to be moved into any position relative thereto when the door is swung into open or closed positions. Lugs 22 and 23 may be formed in the link adjacent the finger 17 which will engage the loop 18 and prevent the link from sliding downward relative to the bracket when the door is closed.

The loop eyelet 14 is of a diameter sufficient to permit the link to slide on the rod 1 from the arm 2 to arm 3 without the possibility of the rod and link interlocking with each other at intermediate portions of the rod. The eyelet 21 of the bracket loop 19 is also of a diameter large enough to provide a universal joint between the link 10 and the bracket 18 to enable the link to be swung through an arc of substantially 45 degrees, the depending fingers 17 being of sufficient length to overcome any tendency of the same from becoming accidentally disengaged from the bracket.

When it is desired to swing the door on an arc of 180 degrees into parallel position relative with the wall 29 of the garage or building to dispose the door out of the way, the hooked end of the link may be withdrawn from the eyelet 21. The flanged fastening arms 4 and 5 of the rod 1 which are preferably disposed parallel to each other and at right angles to the rod 1 to provide a more rigid securing means for the rod 1, whereby the pull and stress on the rod 1 by the link 11 will not readily disengage the rod 1 from the door. The forces are more evenly distributed by virtue of this construction.

I preferably dispose the rod 1, link 11 and bracket 14 on the interior side of the building, thereby reducing possibility of the various parts rusting because of exposure to the elements.

Referring to Fig. 7, I show a modified mounting for a vertically disposed rod upon which the link 10 may slide, comprising a pair of opposed similar brackets 80 and 81 secured to a support, such as a door as in the case of the flanges 4 and 5 of the foregoing embodiment, by their vertical portions, and having oppositely aligned depressions 82 in the mid portions of their horizontal portions 84 into which depressions the ends of a rod 1' are telescoped. One of the brackets is first secured to the support and the end of the rod 1' is then placed in the depression and the other bracket is then properly aligned with the opposite end of the rod disposed in the depression at which time the second bracket is secured to the support.

Having thus described my invention in a specific embodiment, I am aware that numerous and extensive departures may be made from the embodiments herein illustrated and described, but without departing from the 70 spirit of my invention.

I claim:

1. In a door holder, the combination with a pair of abutting portions of the door and door jamb disposed adjacent the hinged edge 75 of the door of a pair of interlocked securing elements for the door, each being secured to one of the said portions, one of said elements comprising a link adapted to be swiveled at an end to one of the portions and terminating at the other end in an eyelet, said eyelet being disposed at an obtuse angle to the longitudinally extending intermediate portion of the link, the other securing element comprising a pair of brackets having bases 80 rigidly affixed to the other said portion in spaced relation, one above the other, substantially parallel to the adjacent door edge, and each comprising horizontally extending flanges, and a pin rigidly held between the 85 flanges and passed through said eyelet, the bottom bracket having its horizontal flange portion disposed below the level of the swiveling end of the link.

2. In a door holder, the combination with 95 a pair of abutting portions of the door and door jamb disposed adjacent the hinged edge of the door of a pair of interlocked securing elements for the door, each being secured to one of the said portions, one of said elements comprising a link adapted to be swiveled at an end to one of the portions and terminating at the other end in an eyelet, said eyelet being disposed at an obtuse angle to the longitudinally extending intermediate portion of the link, the other securing element comprising a pair of brackets having bases rigidly affixed to the other said portion in spaced relation, one above the other, substantially parallel to the adjacent door edge, and each comprising horizontally extending flanges, and a pin rigidly held between the 100 flanges, one of said flanges being provided with a recess, and an end of said pin being projected within the recess, the bottom bracket having its horizontal flange portion disposed below the level of the 105 swiveling end of the link.

3. In a door holder, the combination with 115 a pair of abutting portions of the door and door jamb disposed adjacent the hinged edge of the door of a pair of interlocked securing elements for the door, each being secured to one of the said portions, one of said elements comprising a link adapted to be swiveled 120 at an end to one of the portions and terminating at the other end in an eyelet, said eyelet being disposed at an obtuse angle to the longitudinally extending intermediate portion of the link, the other securing ele- 125 130

ment comprising a pair of brackets having bases rigidly affixed to the other said portion in spaced relation, one above the other, substantially parallel to the adjacent door edge, 5 and each comprising horizontally extending flanges, and a pin rigidly held between the flanges, said flanges being provided with op-

posing recesses receiving the ends of the pin, the bottom bracket having its horizontal flange portion disposed below the level of 10 the swiveling end of the link.

In testimony whereof I hereunto affix my signature this 10th day of June, 1927.

NORMAN CLAYBAUGH DE LOSS.
